UNITED STATES PATENT OFFICE.

EDWARD T. BURGESS, OF CORNING, NEW YORK.

DESIGN FOR GLASSWARE.

SPECIFICATION forming part of Design No. 13,042, dated July 18, 1882.

Application filed May 15, 1882. Term of patent 7 years.

To all whom it may concern:

Be it known that I, EDWARD T. BURGESS, of the village of Corning, in the county of Steuben and State of New York, have invented 5 a new and original Design to be Cut into or upon Glassware for the purpose of ornamenting the same; and I do hereby declare that the following is a full and clear description of the same, reference being had to the annexed 10 drawing, (Patent Office No. 61,320,) which makes a part of this description and specification.

This design is a combination of stars, octagons, and irregular hexagons formed by three 15 series of parallel miter cuts or grooves cut

into the surface of any glassware. Such miter cuts or grooves are represented in the annexed drawing by lines A A, B B, and C C, cut or running across the surface at the respective angles of 28° , 73° , and 0° , so as to form said 20 figures and faces, as shown.

I claim—

The miter cuts or grooves A A, B B, and C C, at their angles and in their relative positions forming the figures and faces as shown. 25

EDWARD T. BURGESS.
